UNITED STATES PATENT OFFICE.

BARNETT SHATZ, OF BUENOS AIRES, ARGENTINA.

DEVICE TO GRADUATE THE DISTANCE OF THE LINES OF TYPEWRITING-MACHINES, SPECIALLY FOR WRITING ON RULED PAPER.

1,401,653.

Specification of Letters Patent. Patented Dec. 27, 1921.

Application filed April 10, 1920. Serial No. 372,940.

To all whom it may concern:

Be it known that I, BARNETT SHATZ, a citizen of the United States of America, residing at Buenos Aires, Argentine Republic, have 5 invented new and useful Improvements in a Device to Graduate the Distance of the Lines of Typewriting-Machines, Specially for Writing on Ruled Paper, of which the following is a specification.

10 This invention relates primarily to variable line spacing mechanisms of a typewriting-machine, the primary object being to enable the operator to obtain mechanically any desired line spacing interval without the 15 delay of repeated trial adjustments, thus gradually facilitating the work and rendering the regulation of the line spacing interval easy and rapid.

It is of course well understood that in typewriting machines as ordinarily constructed, the spacing of the lines is effected by the engagement of a pawl with the teeth of a ratchet-wheel, three spacings being ordinarily provided, which are known as single, 25 double and triple spaces. My improved mechanism is designed to provide greater variation in the line spacing than in lines employing the ordinary three spacings. Should it be required to space irregularly, 30 however, as in filling in blanks, or should a spacing be required other than the three arbitrary spacings provided by the spacing devices now generally in use, or should it be desired to approximately fill a sheet of 35 limited size with a certain number of lines which would not correspond with either of the three arbitrary spacings provided ordinarily, it would be necessary to throw off the ordinary spacing mechanism and space each 40 line by guess work by rotation of the platen, and frequently to shift the paper relatively to the platen. It is also desirable at times to accurately space the printing on ruled sheets of paper and this may be accomplished by 45 my improved mechanism.

A further object of the invention is to provide line spacing mechanism for typewriting machines which may be manufactured at small cost and be readily assembled, 50 and which may be quickly set for any desired width of spacing.

With the foregoing objects outlined and with other objects in view which will appear

as the description proceeds, the invention consists in the novel features hereinafter 55 described in detail, illustrated in the accompanying drawing and more particularly pointed out in the appended claims.

Referring to the drawing:—

Figure 1 is an end view of a type-writer 60 carriage having my improved mechanism attached thereto.

Fig. 2 is a front view of the same end of the typewriter carriage with my mechanism applied. 65

Fig. 3 is a view of my improved mechanism taken from the opposite side from that shown in Fig. 1, and showing the mechanism in normal position.

Fig. 4 is a view similar to Fig. 3 but showing the mechanism during operation. 70

In the drawing, 1 designates a line space wheel provided with a gear toothed periphery. This wheel is fixed on one end portion of the platen spindle 24 which carries the usual platen roller 19. A bell-crank lever having arms 2 and 3 is rotatably mounted on the spindle between the wheel 1 and the adjustable collar 32 which is held in place by the ordinary spindle-head 31. 75 The arm 2 of the bell-crank carries a swinging pawl 5 which is pivotally mounted on a fulcrum screw 8, and a leaf spring 6 is fixed to the arm 2 and engages the pawl 5 for normally maintaining the same out of engagement with the teeth of the wheel 1. A stop surface 4 is provided on the arm 2 to limit the movement of the pawl in the direction in which it is forced by the spring 6. The pawl is swung in one direction in order to engage 80 the teeth of the wheel 1, by means of a pin 15 carried by a push-rod or bar 14 which is slidably mounted in one end 25 of the typewriter carriage. When the rod 14 is reciprocated the pin 15 will strike the upper portion 85 of the pawl and will cause the same to swing on its axis and engage the teeth of the wheel 1. Then the wheel will turn with the pawl. 90

The turning movement of the bell-crank 100 is limited in one direction by means of a fine pitch threaded screw 9 which engages a fixed nut 12 that is secured to the end plate 25 by means of a screw 13. The lower end of the arm 3 of the bell-crank is designed to engage the screw 9 which acts as 105

a fixed stop for the bell-crank and as fine 5 adjustments may be made by the screw 9, the adjustment of the wheel may be made very minute. The screw 9 is provided with a knuckled knob 10 designed to be engaged by the operator for adjusting the screw, and a combined gaging and locknut 11 is mounted on the screw 9 between the head 10 and the fixed nut 12. The nut 11 may be used 10 to lock the screw in any fixed position or it may be utilized to insure that the screw occupies a particular position at all times. In other words, the screw 9 may be adjusted from its position shown in Fig. 1 by unscrewing said screw and this will cause the tightening nut 11 to rise with the screw. Then if the nut 11 is permitted to remain 15 in its original position relatively to the screw 9, the screw may be accurately brought 20 back to its original position by lowering the screw until the nut 11 engages the fixed nut 12. This is a desirable feature in many instances as the screw 9 may be raised to permit say single spacing for a greater or 25 less portion of a page and then the screw may be lowered to bring the nut 11 back to its original position and the mechanism will then half-space or the like.

The push rod 14 is provided with a hand 30 engaging head 18 desired to coöperate with the fixed stop 25 for limiting the rearward movement of the push rod. The push rod also has a stop pin 29 which projects from the opposite side of the rod from that of 35 the pin 15 and which is designed to co-operate with a fixed stop 30 on the end plate of the frame to limit the outward movement of the push rod 14. A coil spring 20 having one of its ends secured to a pin 17 carried by the push rod and its other end 40 connected to a fixed member 21 on the end plate 25, functions to limit the push rod to its normal position. A second coil spring 22 fixed at 23 to the nut 12 and at 28 to the arm 3, is designed to yieldingly hold 45 the arm 3 in engagement with the lower end of the screw 9 and to return the bell-crank to its normal position after it has been turned by the pin of the push rod 14.

50 A cross-shaped leaf spring 26 is fixed by clips 27 to a sleeve 16 mounted on the spindle 24, and functions to maintain the wheel 1 in a definite position.

From the foregoing it will be seen that 55 the adjustment of the screw 9 will enable the platen roller 19 to be shifted various amounts depending on the desire of the operator. When the operator adjusts the screw 9 to the position desired, the push rod 14 may be operated and this will cause the pin 15 to rock the pawl 5 on its fulcrum until said pawl engages the teeth of the line space wheel 1. Then the line space wheel, 60 pawl and bell-crank will turn in unison 65 upon the spindle 24 until the hand engag-

ing member 18 strikes the stop 25. When the operator releases the push rod, the spring 20 will return the same to its normal position and the spring 22 will return the bell-crank into engagement with the screw 9. 70 When the rod 14 is pushed rearwardly it will travel in the direction of the arrow *b* shown in Fig. 4 and the line space wheel will travel in the direction of the arrow *a* in said figure. 75

From the foregoing I believe that the construction and operation of my improved mechanism will be clearly understood by those skilled in the art and I am aware that various changes and modifications may be 80 made in the construction shown without departing from the spirit of the invention as expressed in the following claims.

I claim—

1. In a type-writer, the combination with 85 a platen roller and its spindle, of a toothed wheel fixed to said spindle, a bell-crank lever loosely mounted on said spindle and provided with a pawl designed to engage the teeth of said wheel, means for normally 90 maintaining said pawl out of engagement with the teeth of said wheel, a push-rod having a pin engageable with said pawl to cause the pawl to grip the teeth of the wheel and to turn the wheel and platen roller when 95 the push-rod is operated, and an adjustable screw engageable with the bell-crank lever for limiting the oscillating movement of said bell-crank lever in one direction.

2. In a type-writer, the combination with 100 a platen roller and its spindle, of a toothed wheel operatively connected to said spindle, a movable member carrying a pawl engageable with the teeth of said wheel for causing turning movement of the wheel and 105 platen roller, an operating member engageable with said pawl for causing the same to turn said wheel, an adjustable screw engageable with the first mentioned member for limiting its movement in one direction, 110 and an adjustable stop carried by said screw for use in gaging the extent of movement of the first mentioned member.

3. In a type-writing machine, the combination with a platen roller and its spindle, 115 of a fine toothed wheel fixedly mounted on said spindle, a bell-crank lever pivotally mounted on the spindle, a pawl pivotally mounted on one arm of said bell-crank lever, a spring carried by said arm and engageable with the pawl for normally holding the same out of engagement with the teeth of said wheel, a slidably mounted push-rod having a pin engageable with said pawl for shifting the same about its fulcrum and causing it to engage the teeth of 120 said wheel, a spring for returning the push-rod to its normal position, a second spring 125 for returning the bell-crank lever to its normal position, and an adjustable screw 130

engageable with the other arm of said bell-crank lever for limiting the movement of said bell-crank lever in one direction.

4. A combination of the kind defined by
5 claim 3 in which the adjustable screw is provided with a combined gaging and lock nut.

In testimony whereof he has signed his name to this specification in the presence of two subscribing witnesses.

BARNETT SHATZ.
